Inventor,

William E. Clarke
By his Attorney Geo. W. Tibbitts

UNITED STATES PATENT OFFICE.

WILLIAM E. CLARKE, OF CLEVELAND, OHIO.

STEAM-ENGINE.

SPECIFICATION forming part of Letters Patent No. 415,137, dated November 12, 1889.

Application filed February 28, 1889. Serial No. 301,586. (No model.)

To all whom it may concern:

Be it known that I, WILLIAM E. CLARKE, a citizen of the United States, residing at Cleveland, in the county of Cuyahoga and State of Ohio, have invented certain new and useful 5 Improvements in Condensers for Steam-Engines, of which the following is a specification.

This invention relates to condensers for engines and boilers; and it consists in the combination, with the engine and boiler, of surface condensers joined at their tops with an overhead dome, provided with a discharge-opening having a fan-blower for enhancing 15 the currents of air through the condensers and increasing the draft of the boiler-furnace, as hereinafter described, and pointed out in the claim.

The object of the invention is to provide a 20 cheap and economical means of disposing of exhaust-steam, and is particularly applicable for street-car steam motors.

The invention consists in the peculiar construction and combinations of devices, substantially as hereinafter described, and pointed out in the claim.

In the accompanying drawings, Figure 1 is a longitudinal section of a car and motor having my improved condenser attached. Fig. 30 2 is a transverse section of the same.

A represents a car-body mounted on a truck or trucks.

B represents a boiler, and C a steam-engine motor. These may be of any of the 35 well-known constructions.

D are condensers into which the steam from the engines is exhausted. In the drawings they are represented in the form of chambers located at the sides of the car-body 40 for convenience of arrangement for such vehicles. They might be cylindrical in form, if desirable, in other instances of adaptation. They are provided with open flues d d, extending from bottom to top, the space surround-

ing said flues forming the steam-chamber and 45 the surfaces of the flues forming the steam-condensing surfaces. The tops of the condensers are connected with a hooded dome-shaped chamber E, the central part at the top being provided with a large outlet-pipe F, extending upward through the roof of the car. In the said pipe F is provided a rotary fan G, 50 fixed on a vertical shaft H, having a pulley I, connected by a belt or otherwise with power from the engine for imparting rapid rotary 55 motion to the said fan. The purpose of the fan is for inducing currents of cold air up through the flues d, whose lower ends are open to the cold outer atmosphere, their upper ends leading into the dome-chamber E. 60

J are pipes leading from the exhaust-ports of the engines into the condensing-chambers, where the steam is quickly condensed. The water resulting from the condensation may be removed from these condensers by means 65 of pumps or other suitable means to the water-supply tank for the boiler.

The front of the boiler B is also connected with the dome-chamber F, so that the gases and other products of combustion are discharged out of the pipe F, and the draft of 70 the boiler-furnace is also enhanced.

Having described my invention, what I 75 claim, and desire to secure by Letters Patent, is—

The combination, in a car provided with a steam-boiler and engine, of surface condensers, as D D, having air-circulating flues d d and joined at the top by overhead dome E, having discharge-opening F, in which is provided a fan-blower G, for creating a current of air through said flues d and enhancing the draft in the boiler-furnace, substantially as 80 described.

WILLIAM E. CLARKE.
